UNITED STATES PATENT OFFICE.

THOMAS WATKIN WEAVER AND CLYDE BENNETT WEAVER, OF TUNNELTON, WEST VIRGINIA,
ASSIGNORS OF ONE-THIRD TO SCOTT W. SHAHAN, OF TUNNELTON, WEST VIRGINIA.

MINE-CAR.

No. 926,446.

Specification of Letters Patent.

Patented June 29, 1909.

Application filed October 29, 1908. Serial No. 460,019.

To all whom it may concern:

Be it known that we, THOMAS W. WEAVER and CLYDE B. WEAVER, citizens of the United States, and residents of Tunnelton, 5 in the county of Preston and State of West Virginia, have invented new and useful Improvements in Mine-Cars, of which the following is a full, clear, and exact description.

This invention relates to improvements in 10 mine cars, and more particularly such as dumping cars or the like, and each of which in general is provided with a trigger, a locking member adapted to engage a catch to hold the end gate or door of a car normally in 15 a closed position, and a movable link connecting the trigger and the locking member, means being provided whereby the trigger can be actuated to release the locking member from the catch.

20 The object of the invention is to provide a device of the class described, simple and serviceable in construction, which will securely lock the end gate of a car, and which will be automatically released when the car 25 has reached a predetermined point, so that the contents of the car will be easily discharged.

Reference is to be had to the accompanying drawings forming a part of this specification, 30 in which similar characters of reference indicate corresponding parts in both views.

Figure 1 is a perspective view showing an embodiment of our invention applied to a 35 mine car; and Fig. 2 is an enlarged perspective view showing our invention in detail and with the gate closed.

In the specific form shown in the drawings, 1 represents a car of any common or preferred form, having an end gate 2. Extending around the end of the car and being substantially U-shaped in form, is an elongated strip 3, the latter having its ends 4 extending above the upper edge of the car. The ends 40 4 have openings 5 extending therethrough which constitute bearings adapted to receive the ends of a support 6, preferably circular in cross section. Cotter pins 7 serve to secure the support at the ends 4 of the elongated 45 strip.

Located on the gate 2 are members or straps 8, the latter having their upper ends 9 curved over the support 6, so that the latter will movably carry the gate. Arranged on 50 the outside of the end gate is a bracket 10

having outwardly disposed extensions 11 provided with registering openings 12. Pivotedly secured between the extensions 12 by means of a pin 13 is a trigger 14, preferably in the form of a bell crank lever, and having 60 its upper end 15 extending above the support 6. The lower end 16 of this trigger is outwardly disposed and bifurcated, as shown most clearly in Fig. 2 of the drawings.

Slidably secured to the gate is a link 17 65 having its upper portion 18 outwardly disposed and terminating between the bifurcated ends 16 of the trigger, where it is pivotally held by means of a rivet or pin 19. Guides 20, secured to the gate, serve to hold 70 this link in place. The lower end 21 of the link is cut away and broadened to form a foot. Located on the link near the lower end thereof, is an extension 22 having an opening extending therethrough. Pivotedly 75 secured at this extension by means of a rivet 23 or the like, which extends through its upper bifurcated portion, is a locking member 24. Secured to the floor of the car is a catch 25 which has its outer end 26 upwardly 80 disposed and adapted to receive the lower end of the locking member 24, so that the end gate of the car will be held against accidental displacement.

Located at any suitable point adjacent to 85 the track is a stop 27, which is adapted to engage the upper end 15 of the trigger to actuate the same when the car has reached a predetermined point, at which its contents are to be discharged, as illustrated in Fig. 1 90 of the drawings.

In the form shown, the stop is secured to the frame of a building and extends downwardly therefrom. When the trigger has come in contact with the stop, it is so actuated that through the medium of the link 17, the locking member 24 is drawn out of engagement with the catch 25, and the end gate, against which constant pressure is being brought to bear by the weight of the contents 100 of the car, will swing open and permit the discharge of the same.

Having thus described our invention, we claim as new and desire to secure by Letters Patent:

1. In combination with a mine car, a catch on the car a swinging end gate, a link slidably mounted on said end gate, a trigger pivotally secured to said link and said gate, and a locking member pivotally carried by 110

said link and adapted to engage said catch to hold said gate in a locked position.

2. In combination with a mine car, a catch on the car a swinging end gate, a link 5 slidably mounted on said end gate, a trigger pivotally secured to said link and said gate, and a locking member pivotally carried by said link and adapted to engage said catch to hold said gate in a locked position, and means 10 adapted to engage said trigger for actuating the same whereby said gate will be released to permit the discharge of the contents of the car.

3. In a mine car provided with a swinging

end gate, a catch on the car, a locking member slidable on the gate for engaging the catch to hold the gate in locking position, a trigger pivoted to the gate and having one end connected with the locking member for the purpose set forth.

In testimony whereof we have signed our names to this specification in the presence of two subscribing witnesses.

THOMAS WATKIN WEAVER.
CLYDE BENNETT WEAVER.
